**DRIVES FOR AUTOMATIC MINING MACHINES
OF THE PLANER TYPE**

Günther Dommann, Wethmar, near Lunen, Germany

Application August 23, 1954, Serial No. 451,504

4 Claims. (Cl. 262—8)

This invention relates to improvements in drives for automatic mining machines. It more particularly relates to an improved drive for an automatic mining machine provided with a longitudinally extending conveyor and a device movable back and forth along the conveyor for removing mineral such as coal and depositing same in the conveyor.

Automatic mining machines for the mining and/or loading of mineral such as coal are known. Such machines for use in long wall mining may consist of a longitudinally extending conveyor which is positioned along and adjacent to the mine face. A coal removing device is moved back and forth along the conveyor for removing coal from the mine face and depositing the same in the conveyor. As the coal is removed from the face, the conveyor and mining device may be continuously advanced. The conveyor may have an upper trough shaped portion through which flights of scrapers move. The scrapers may be connected at each end to endless chains or the like which are rotated. The coal is deposited in the trough and continuously conveyed by means of the scraper flights.

One embodiment of such an automatic mining machine known as a "coal planer," a planer cutting head is drawn back and forth along the forward longitudinal side of the conveyor, preferably in guided relation thereto by means of a flexible traction element such as a chain. The planer cutter head cuts in each direction of movement and has an inclined surface somewhat in the shape of a plow which guides the cut coal into the conveyor.

In mining planers and other similar mining machines, a common drive may be provided for operating the conveyor and pulling the mining device, such as the planer cutter, back and forth along the conveyor. Since, as is well known, the starting friction is greater than the running friction, the power required to start the scraper flight of the conveyor is generally about three times the power required to operate the same. As the power installation must be sufficient to start the conveyor, the same has a large power reserve which is not utilized during operation.

In units provided with a common drive for the conveyor and mining device such as the planer cutter, the mining device may be connected to the drive with a disengageable coupling which makes possible temporary stoppage of the mining device. In this manner, the entire power of the drive is available for driving the conveyor and may be utilized for the initial starting of the same. When the conveyor is in operation, the excess power is utilized for operation of the mining device by engaging the coupling again.

In devices as described above with a common drive for the conveyor for the mining device, the traction element of the mining device such as the chain which pulls the planer head is driven in all cases for any given direction of motion from only one end of the conveyor, even if identical driving stations are provided at both ends of the

conveyor. The forces necessary to pull the mining device, such as the planer cutting head, are, therefore, exerted completely through a single drive gear. When using a chain as a traction element, the entire suspended chain must be centralized at this point. A back and forth motion of the mining device, such as the planer cutter head, is only possible by changing the driving station and not by changing the direction of operation of the drive gears since the conveyor is always driven in a single direction. In order to effect this reversing, the traction element, such as the chain, must be conducted from one drive station to the other. A subdivision of the drive of the mining machine by the insertion of a reversal station between the ends of the conveyor is thus not possible. This, however, in practical operation is a serious disadvantage, particularly when operating on long wall mine faces which are traversed by faults. The traction element, such as the chain, extends over the entire length of the conveyor whereas the mining device, such as the planer cutting head, will only be operated over a part of the conveyor length as, for example, between the fault and the driving station. The extension of the traction element over the length of the conveyor, however, prevents the manual preparatory work in the fault zone and endangers the additional support which is generally necessary at that place.

If the conveyors and the mining device as, for example, the planer cutting head, are provided with separate drives, the above mentioned disadvantage is eliminated. The pulling of the traction element of the mining device, such as the chain, can be effected simultaneously from drive stations positioned at each end of the conveyor. The back and forth motion is effected by reversing the direction of operation of the sprocket wheels. In this connection, the pulling forces exerted by both drive members are reduced so that only one half of the force is exerted by each drive. In this connection, the insertion of intermediate reversing stations or drives is possible. Accordingly, separate plows can operate along different sections of a single continuous conveyor. With separate drives, however, the drive for the conveyor must have an increased power sufficient to start the same. This power is, of course, not utilized and wasted during normal operation.

One object of this invention is a drive for a conveyor and mining device of a type described above which incorporates the advantages of the two above mentioned systems, while eliminating the disadvantages thereof. This and still further objects will become apparent from the following description read in conjunction with the drawing which shows a diagrammatic plan view of an embodiment of a drive in accordance with the invention.

In accordance with the invention, a separate drive is provided for the conveyor and for the mining device such as the planer cutting head. The drive for the conveyor is preferably a direct drive. The drive for the mining device is an indirect drive which may be connected to assist in the driving of the conveyor for its starting. The drive for the mining device is preferably connected thereto through a disengageable coupling. The mining device drive may be constructed so that the same is reversible or may be connected to drive the mining device through a reversing gear. An automatic locking device is preferably provided which prevents a coupling of the conveyor drive and the mining device drive when the same are operating in opposite directions of rotation. With two drives for the mining device provided with couplings reversing gears for moving the mining device in each direction of motion, the same are advantageously so connected with each other that they may be shifted from one direction to the other jointly.

Referring to the embodiment as shown in the drawing, the motor 1 drives the drive drum 3 of the conveyor 4 through the gearing 2. As the drive drum 3 rotates, the chains which pass over each end thereof carry along the scraper flights which convey the coal. The motor 1 is preferably so dimensioned and powered that it has sufficient power to operate the conveyor 4 during all the normal operating conditions, but does not have sufficient power to initially start the same in operation. Therefore, in operation of the conveyor, the power of the motor 1 is fully utilized and there is no excess power which is wasted.

The motor 5 on the other side of the conveyor through the gearing 6 drives the sprocket wheel 7 over which the chain 8 passes. The chain 8 in turn drives the shaft 13 by means of the sprocket wheel 9. The shaft 13 thus rotates with the motor 5 and contains two disengageable fluid couplings 10 and 14 at each end. The disengageable fluid coupling 10 when engaged causes the shaft 13 to drive the sprocket wheel 11 which in turn actuates the endless traction element 12 in the form of a chain to which the mining device, such as a planer cutting head, is attached. The disengageable fluid coupling 14 when engaged causes the shaft 13 to drive the sprocket wheel 15. The sprocket wheel 15 is in turn connected by means of a chain 16 to the sprocket wheel 17 which is mounted on the shaft 18.

In operation, in order to start the conveyor 4, the fluid coupling 10 is disengaged so that the shaft 13 will not drive the sprocket wheel 11 and the fluid coupling 14 is engaged so that the shaft 13 will drive the sprocket wheel 15. The motors 5 and 1 are then started. The motor 1 through the gearing 2 directly drives the shaft 18 and the drive drum 3. The motor 5 through the gearing 6, sprocket wheels 7 and 9 and chain 8, drives the shaft 13. The shaft 13 in turn drives the sprocket wheel 15, the chain 16, sprocket wheel 17, the shaft 18 and thus the drum 3. The combined powers of the motors 1 and 5 are thus exerted on the conveyor and the motor 5 supplements the power of the motor 1 so that sufficient power is exerted on the drum 3 to overcome the initial starting friction and bring the conveyor to its operating speed. Once at its operating speed, the additional power of the

drive 5 is not required and the coupling 14 is disengaged so that the motor 1 solely drives the conveyor. The coupling 10 may then be engaged so that the mining device, such as the planer cutting head, is drawn back and forth along the conveyor by means of the chain 12 driven over the sprocket wheel 11.

I claim:

1. A drive for an automatic mining machine provided with a longitudinally extending conveyor and a mining device pulled back and forth along said conveyor by a flexible traction element, which comprises a first drive motor, means connecting said first drive motor to the conveyor for the driving actuation thereof, a second drive motor, first disengageable means connecting said second drive motor to said conveyor for the driving actuation thereof, and second disengageable means connecting said second drive motor to said flexible traction element for the driving actuation thereof.
2. Drive according to claim 1 including a rotatable shaft connected for rotation with said second drive motor, and in which said first disengageable means includes a disengageable coupling connected to said shaft and said second disengageable means includes a second disengageable coupling connected to said shaft.
3. Drive according to claim 1 in which said second drive motor is a reversible drive motor.
4. Drive according to claim 1 in which said means connecting said second drive motor to said flexible traction element includes a reversing gear.
